UNITED STATES PATENT OFFICE.

JOHN J. N. VAN HAMERSVELD AND HAL L. COOK, OF CLEVELAND HEIGHTS, OHIO, ASSIGNEES, BY MESNE ASSIGNMENTS, TO THE ROTOR AIR TOOL COMPANY, OF CLEVELAND, OHIO, A CORPORATION OF OHIO.

ROTARY-MOTOR TOOL.

Application filed November 21, 1925. Serial No. 70,642.

This invention relates to rotary motor tools, and has for one of its objects to provide a construction which simplifies and facilitates the assembly of the parts, which minimizes liability of misalignment of the shaft bearings, and which admits of reduced clearance between the rotary pistons and the walls of the cylinders resulting in increased power and speed.

10 A further object is to so form the inlet and outlet ports and passageways through the cylinder body, that uniformity and accuracy are obtained in the sizes of the ports, and the cost of manufacture is reduced since 15 the ports and passageways are formed almost entirely by drilling operations.

20 A still further object is to so form and arrange the valve controlling the air or other fluid pressure as to permit the ready manipulation of the valve when the tool is in the hands of the operator, and at the same time provide a more direct flow for the motive fluid than heretofore, with the result that there is less skin friction and loss of 25 power.

The above and other objects are attained by the present invention, which may be briefly summarized as consisting in certain novel details of construction, and combinations and arrangements of parts which will 30 be described in the specification and set forth in the appended claims.

In the accompanying sheets of drawings 35 wherein we have shown the preferred embodiment of the invention, Fig. 1 is a top plan view of a rotary grinder with a motor constructed in accordance with our invention, the top cap and gasket being removed; Fig. 2 is a longitudinal sectional view of the same, the pistons being in elevation; Fig. 3 is a transverse sectional view substantially along the line 3—3 of Fig. 2; Fig. 4 is a transverse sectional view substantially along the line 4—4 of Fig. 1, omitting a portion of the end bracket; Fig. 5 is an enlarged longitudinal sectional view omitting portions of the handles or end brackets; Fig. 6 is a transverse sectional view substantially along the line 6—6 of Fig. 5; Fig. 7 is a longitudinal sectional view through the center of the cylinder body; Fig. 8 is a sectional view through the cylinder body, substantially 50 along the line 8—8 of Fig. 7; Fig. 9 is a

fragmentary sectional view through a portion of the handle bracket, substantially 55 along the line 9—9 of Fig. 10, showing particularly the valve by which the motive fluid is controlled, and certain of the passageways therefor through the end bracket, end plate and the cylinder body; Fig. 10 is 60 a sectional view substantially along the line 10—10 of Fig. 9; Fig. 11 is a sectional view of the valve showing the inner adjustable member displaced from normal position to reduce the effective size of the valve opening. 65

The motor includes a cylinder body or casting 15, shown detached in Figs. 7 and 8, and two handle members or end brackets 16 and 17, which are secured to opposite ends of the cylinder body, with intervening end plates 18 and 19. The end bracket 16 in this instance has a straight handle portion 16^a arranged opposite, and in line with the spindle 20, the motive fluid, in this instance air, being introduced through this end 75 bracket and its handle portion, and the valve controlling the air flow being carried by the bracket.

The other bracket 17 has a sleeve-like extension 17^a constituting a handle portion, 80 this sleeve-like extension being concentric with the spindle 20 which extends through the extension, as shown, and is provided at its outer end with a suitable tool, in this instance, a grinding wheel 21, partially enclosed in a guard 22, which is secured onto the end of the extension of the bracket. 85

The cylinder body is provided with two cylinders which accommodate two eccentric pistons 23 and 23, preferably keyed to the shaft and arranged 180° apart. (See Fig. 5). In forming the cylinders, the cylinder body 15 is given a straight bore 15^a extending from end to end thereof. (See Fig. 7). The cylinders are formed by the cylinder body, the two end plates 18 and 19, and an intermediate member 24 which separates the cylinders, and in this instance constitutes a housing for a center anti-friction bearing 25 for the spindle 20. The spindle 90 is supported by the bearing 25, just referred to, and a second anti-friction bearing 26 which is located at the outer end of the sleeve-like extension 17^a of end bracket 17, this arrangement of the bearings being one 95 of the important parts of the present invention.

tion, it being a feature thereof that the spindle is supported independently of the end bracket 16. By reason of the fact that the bearing 25 is located between and close to both pistons it is obvious that a slight error in the location of bearing 26 will have much less effect on the pistons than if the bearing 24 were located in the end bracket 16, and furthermore, since the spindle and therefore the pistons are supported independently of bracket 16, it is obvious that careful alignment in so far as the assembly of this bracket to the cylinder body is concerned is unnecessary. This arrangement of bearings admits of a much closer appearance than heretofore between the pistons and the cylinder-forming portions of the cylinder body, resulting in a better sealing effect, reducing leakage and giving increased speed and power.

The end brackets 16 and 17, the end plates 18 and 19 and the cylinder body are all secured together by a series of parallel bolts 27 arranged preferably 90° apart, as illustrated in Figs. 6 and 10.

Between two of the bolts 27 the cylinder body is provided with an extension 15^b (see Fig. 6) through which extends an air inlet passageway 28 and an air outlet passageway 29 which are formed by drilling openings longitudinally through the extension of the cylinder body, from end to end thereof. Additionally this extension accommodates two radially movable abutment blades 30, the inner ends of which engage the outer annular surfaces of the two pistons. These abutment blades are slidingly supported in two radial slots 15^c, which are machined inward from opposite ends of the cylinder body, leaving between them a solid portion 15^d. These slots 15^c extend from the flat outer portion of the extension 15^b, through the annular cylindrical wall of the cylinder body. Additionally there are formed through the extension 15^b of the cylinder body, two series of inlet passageways 31 which are drilled from the outer flat face of the extension entirely through it so as to communicate with the cylinders, and these passageways intersect the main axial inlet passageway 28, as shown in Fig. 6 and in Fig. 8. The cylinder body extension 15^b is provided also with a series of exhaust passageways 32 which are drilled in a similar manner through the extension, these exhaust passageways intersecting the main exhaust passageway 29 extending in an axial direction through the extension 15^b.

As shown in the drawings, the inwardly extending inlet passageways 31 are on one side of the slots 15^c which accommodate the abutment blades, and the inwardly extending exhaust passageways are on the opposite side of said slots. The outer ends of the inlet passageways 31 are connected by slots 31^a with the outer portions of the slots 15^c which receive the abutment blades, so that the pressure of the air will be exerted down on the abutment blades, causing them at all times to be pressed against the pistons 23. (See Figs. 1 and 6.) The cylinder body extension 15^b additionally has a double row of laterally extending passageways 29^a extending from the main axial exhaust passageway 29 to the atmosphere, (see Figs. 6 and 8,) the passageways 29^a extending outwardly from the main exhaust passageway 29 at closely spaced points for practically its full length.

The outer ends of the inlet passageways 31, of the outlet passageways 32 and of the abutment blade-receiving slots 15^c are closed by a plate 34 which covers the outer flat face of the cylinder body extension 15^b, and is secured thereto by a series of screws 35, there being preferably provided between the plate 34 and the outer face of the cylinder body extension, a packing strip or gasket 34^a of suitable material, the same sealing the several passageways and slots referred to, against leakage at this point.

It is to be noted that the housing 24 for the center bearing 25 is annular in form, and has a close fit in the cylinder bore 15^a of the cylinder body. Likewise it will be noted that in thickness this housing is the same as the thickness of the portion 15^d between the slots 15^c for the abutment blades. This housing and the bearing will be accurately located in the cylinder body, and when so located are locked in that position by a holding screw 36 extending through the portion 15^d of the cylinder body and through the outer portion of the bearing housing 24, as clearly illustrated in Fig. 5, the head of the screw being beneath the plate 34 so that access may be had to it by removing the plate. By properly locating and holding in position the bearing housing 24 in the manner stated, or in some equivalent way, the sides of the housing 24 form continuations of the ends of the slots 15^c in the cylinder body extension, and the inner ends of the abutment blades 30 slide freely over the sides of the bearing housing 24 as well as the walls formed by the inner ends of the slots 15^c, just as effectively as the outer ends of the blades slide over or on the end plates 18 and 19, which plates, as before stated, form the outer ends of the cylinders as well as close the outer ends of the slots 15^c.

It will be noted before passing to other novel features to be referred to, that by reason of the fact that the cylinder bore 15^a and the inlet and outlet passageways 28 and 29 extend axially entirely through the cylinder body, and as the slots 15^c, inlet passageways 31 and exhaust passageways 32 extend entirely through the cylinder body extension 15^b and the short slots 31^a and lateral

exhaust passageways 29^a extend entirely through the walls in which they are formed, the cylinder body as a whole can be readily and accurately machined, and since the construction is such that none of the passageways for the air are formed by casting the same into the cylinder body, a greater degree of uniformity and accuracy is obtained than if the openings were cored or cast in the body.

Air or other motive fluid is supplied to the end of the handle portion 16^a of the end bracket 16 at a connection indicated at 33. This communicates with a passageway 34 extending lengthwise of the handle portion 16^a and leads to an extension 16^b of the handle portion 16^a, this extension having a chamber receiving a cylindrically shaped hollow rotary valve 35, whose axis is parallel to the axis of the motor. The valve 35 has a stem 35^a which projects out through the back of the extension 16^b, and at the outer end of this stem, above the handle portion and in close proximity thereto is a valve lever 35^b of the butterfly type, so positioned with respect to the handle portion 16^a, that the operator with his thumb or finger can rotate the valve in either direction while retaining his grip on the handle.

The valve 35 is fitted into a sleeve 36, which is forced into the valve chamber of the extension 16^b, this sleeve having a port 36^a in line with the passageway 34, as indicated in Fig. 2, and the valve having a similar port 36^b leading to its interior. This last mentioned port is adapted to be brought into and out of alignment with the port 36^a so as to start or stop the flow of air, and, in fact, to control it so as to control the speed of the motor. A suitable spring 37 (see Fig. 9) is located between the back wall of the extension 16^b and the lever 35^b so as to prevent leakage of air out around the stem of the valve, and to hold the valve in any position in which it may be turned by the operator.

The valve chamber in the extension 16^b, as well as the opening in the valve proper, face toward the cylinder body, and the inner portion of the valve chamber has a lateral extension 38 (see Figs. 9 and 10) which communicates with the main inlet passageway 28 extending longitudinally through the cylinder body, as best indicated in Fig. 9.

Thus when the valve is turned so as to admit air to the cylinder body and cylinder, the air flows from the passageway 34 in the handle portion 16^a through the bushing 36, and into the hollow valve 35, and from the latter through the extension 38 into the main inlet passageway of the cylinder body, and from this passageway it passes by the passageways 31 into the cylinders.

By this construction we obtain a more direct flow of air from the inlet connection to the cylinders than has heretofore been

attained in motors of this type, and we find that by accurate tests there is a reduction in loss of power due to skin friction and eddying, with a consequent increase of power and speed. Additionally as before stated, the valve lever can be conveniently operated or turned in either direction without requiring that the operator remove or change his grip on the handle portion 16^a.

I may, if desired, place inside of the hollow valve 35, an adjustable sleeve 35^c, as illustrated in the drawings and shown most clearly in Figs. 9 and 11. This sleeve 35^c is normally fixed with relation to the valve, and in this instance is secured thereto by a screw 35^d which passes through the closed end of the sleeve and into the stem of the valve. This inner sleeve is provided with a port 35^e which is of the same size as the port in the valve proper, and normally the ports of the valve and sleeve are in full registration, but if desired, the inner sleeve can be adjusted circumferentially so as to reduce the effective size of the valve port so as to better adapt the tool for varying air pressures. Assuming that the tool is designed for its most efficient or effective use on a given air pressure in the supply line, by adjusting the inner sleeve, the tool will work equally well on a higher pressure.

The motor is amply lubricated automatically by lubricant which is supplied to the air stream passing through the passageway 34, and to accomplish this there is provided in the handle portion 16^a, a lubricant chamber 39 which extends lengthwise through the handle portion parallel with the air passageway 34. Communication is established between lubricant chamber 39 and passageway 34 just in advance of the valve, through a port 40 controlled by a needle valve 41, which can be adjusted to vary the rate of flow of oil. Access may be had to the needle valve 41 by removing a sealing screw 42 (see Fig. 3), and after adjustment, the needle valve can be locked in position by a locking screw 43. Lubricant is designed to be supplied to the chamber 39 by the removal of a screw plug 44, which is shown in Fig. 4.

It will be seen from the above, that we have provided a rotary motor which has high efficiency, and which, because of the refinements in construction, may be operated at high speed. Likewise, it will be seen that by the manner in which the ports and passageways are formed, not only is uniformity and accuracy obtained to a high degree, but the drilling and other machining can be done with rapidity, and the motors can be made in quantities at a relatively low cost.

While we have shown the preferred construction, we do not desire to be confined to the exact details or arrangements shown, but aim in our claims to cover all modifications.

which do not involve a departure from the spirit and scope of the invention as defined in the appended claims.

Having described our invention, we claim:

5. 1. In a rotary motor, a cylinder body having a cylinder bore formed from end to end thereof, said cylinder body having a sleeve-like extension at one end thereof, a shaft extending through said sleeve-like extension and having a pair of eccentric pistons rotatable in the cylinder bore, abutment blades slidably mounted in the cylinder body and at their inner edges engaging the pistons, said shaft having a single bearing 70 in the cylinder body, said bearing being located between the pistons and having a second bearing remote from the cylinder body and located adjacent the outer end of said sleeve-like extension.
10. 2. In a rotary motor, a cylinder body having a cylindrical bore formed from end to end thereof, and having two radially disposed slots for abutment blades extending from opposite ends of the cylinder body 80 inwardly toward the center and both communicating with the cylinder bore, there being between the slots a solid portion, a rotor having two eccentric pistons in the cylinder body, and a separate member fitted 85 in the bore between the pistons inside said solid portion.
3. In a rotary motor, a cylinder body having a cylinder bore formed from end to end thereof, and having an extension provided with inlet and outlet passageways extending through the extension from end to end of the cylinder body in parallel relation with the cylinder bore, and said extension being provided with radial slots extending inwardly from opposite ends of the cylinder body and from the outer face of the extension of said cylinder bore. 100
4. In a rotary motor, a cylinder body having a cylinder bore formed from end to end thereof and provided with a lateral extension, main inlet and exhaust passageways formed through said extension from end to end of the cylinder body in parallel relation with the cylinder bore, and inlet and exhaust passageways formed through the extension at right angles to said main passageways and extending from the outer face of the extension to said cylinder bore. 105
5. In a rotary motor, a cylinder body having a cylinder bore formed from end to end thereof and adapted to accommodate a shaft having two pistons, main inlet and exhaust passageways formed through the cylinder body from end to end thereof in parallel relation with said cylinder bore, a pair of radial slots arranged in alignment and extending from the outer face of the cylinder body inwardly to the cylinder bore, each extending inwardly from one end of the cylindrical body, said slots being located 115
- between said main inlet and exhaust passageways, inlet passageways extending through the wall of the cylinder body on one side of the slots and intersecting the main inlet passageway, and exhaust passageways extending through the wall of the cylinder body on the opposite side of said slots and intersecting the main exhaust passageway. 120
6. In a rotary motor, a cylinder body 75 having a cylinder bore formed from end to end thereof and adapted to accommodate a shaft having two pistons, main inlet and exhaust passageways formed through the cylinder body from end to end thereof in parallel relation with said cylinder bore, a pair of radial slots extending from the outer face of the cylinder body inwardly to the cylinder bore, each extending inwardly from one end of the cylinder body, said slots being located between said main and exhaust passageways, inlet passageways extending through the wall of the cylinder body on one side of the slots and intersecting the main inlet passageway, and exhaust passageways extending through the wall of the cylinder body on the opposite side of said slots and intersecting the main exhaust passageway, the outer ends of said last mentioned inlet passageways communicating with the outer 130 portions of said slots. 125
7. In a rotary motor, a cylinder body having a cylinder bore formed from end to end thereof and adapted to accommodate a shaft having two pistons, main inlet and exhaust passageways formed through the cylinder body from end to end thereof in parallel relation with said cylinder bore, a pair of radial slots extending from the outer face of the cylinder body inwardly to the cylinder bore, each extending inwardly from one end of the cylinder body, said slots being located between said main and exhaust passageways, inlet passageways extending through the wall of the cylinder body on one side of the slots and intersecting the main inlet passageway, and exhaust passageways extending through the wall of the cylinder body on the opposite side of said slots and intersecting the main exhaust passageway, and said cylinder body having exhaust passageways extending transversely through the wall thereof from the main exhaust passageway to the outer side of the cylinder body, said last mentioned passageways being in spaced relation from substantially one end of the cylinder body to the other. 135
8. In a rotary motor tool, a cylinder body having a cylinder bore formed from end to end thereof, a shaft having two pistons adapted to rotate in said cylinder bore, radial slots extending inwardly from opposite ends of the cylinder body toward the center, members at the ends of the cylinder 140

- body forming two end walls of two cylinders formed in the cylinder bore, a center bearing for the shaft and a housing for the bearing located between the pistons and between said slots, means extending through the cylinder body between the slots for locking said housing in position, and abutment blades slidable in said slots on opposite sides of the housing.
9. In a rotary motor tool, a cylinder body having a bore extending from end to end therethrough, an extension having main inlet and exhaust passageways extending from end to end thereof in parallel relation with the cylinder bore, radial slots extending from the outer face of the extension to the cylinder bore and extending from the outer ends of the cylinder body inwardly toward the center, inlet and exhaust passageways located on opposite sides of the slots and extending from the outer face of the extension to the cylinder bore, the last mentioned inlet passageways intersecting said main inlet passageway and the exhaust passageways intersecting said main exhaust passageway, abutment blades slidable in said slots and at their inner edges engaging the pistons, and a removable cover on the outer face of said extension.
10. In a rotary motor tool, a cylinder body having a bore extending from end to end therethrough, an extension having main inlet and exhaust passageways extending from end to end thereof in parallel relation with the cylinder bore, radial slots extending from the outer face of the extension to the cylinder bore and extending from the outer ends of the cylinder body inwardly toward the center, inlet and exhaust passageways located on opposite sides of the slots and extending from the outer face of the extension to the cylinder bore, the last mentioned inlet passageways intersecting said main inlet passageway and the last mentioned exhaust passageways intersecting said main exhaust passageway, abutment blades slid able in said slots and at their inner edges engaging the pistons, a center bearing for the shaft, a housing for said center bearing located between the pistons and the blades, locking means for the housing extending through the extension between the blades, and a cover plate for the outer face of said extension and covering said locking means and the outer portions of the slots and of the last mentioned inlet and exhaust passageways.
11. A rotary motor tool comprising a casing having brackets at the ends thereof, a shaft having one or more pistons in the cas-
- ing, said shaft extending through one of said brackets, the other bracket having a handle portion located opposite the shaft and provided with an air passageway and with a rotatable valve offset laterally from the shaft and having an inwardly facing chamber formed on the inner face of the bracket and adapted to be placed in communication with said passageway, and said valve having a lever adjacent the said handle portion.
12. A rotary motor tool comprising a casing having one or more cylinders, brackets at the ends of said casing, one bracket having a sleeve-like extension constituting a handle portion, a shaft projecting through said extension and provided with one or more pistons in the casing, the other bracket having a handle portion substantially in line with the shaft, said handle portion having a fluid passageway extending lengthwise therethrough and having a valve chamber communicating with said fluid passageway and directly with the casing, said valve chamber being offset laterally from said shaft and extending into the bracket from the inner face thereof, and a hollow valve in said chamber adapted to open and close the communication between said passageway and the casing and having an opening therein which faces or communicates with the chamber.
13. A rotary motor tool comprising a casing having one or more cylinders, brackets at the ends of said cylinders, one bracket having a sleeve-like extension constituting a handle portion, a shaft projecting through said extension and provided with one or more pistons in the casing, the other bracket having a handle portion substantially in line with the shaft, said handle portion having a fluid passageway extending lengthwise therethrough and having a valve chamber communicating with said fluid passageway and directly with the casing, said valve chamber being offset laterally from the shaft and extending into the bracket from the inner face thereof, a hollow valve in said chamber adapted to open and close the communication between said passageway and the casing, and said handle portion having also a lubricant chamber extending longitudinally thereof and having a delivery port communicating with said passageway.

In testimony whereof, we hereunto affix our signatures.

JOHN J. N. VAN HAMERSVELD.
HAL L. COOK.
